(57) **CLAIM**

The ornamental design for a body for hair brush, as shown and described.

DESCRIPTION

FIG. 1 is a perspective view of a body for hair brush showing my new design;

FIG. 2 is a front elevation view thereof;

FIG. 3 is a rear elevation view thereof;

FIG. 4 is a left elevation side view thereof;

FIG. 5 is a right elevation side view thereof;

FIG. 6 is a top plan view thereof;

FIG. 7 is a bottom plan view thereof; and,

FIG. 8 is the perspective view of FIG. 1 illustrating the body for hair brush coupled to a different lower portion.

The broken lines in the drawings depict features that form no part of the claimed design.

1 Claim, 4 Drawing Sheets
